(57) **CLAIM**

The ornamental design for a surgical saw blade teeth, as shown and described.

DESCRIPTION

FIG. 1 is a top view of a surgical saw blade teeth, the bottom view being an identical image thereof;

FIG. 2 is a left side elevation view of the surgical saw blade teeth of FIG. 1, the right side elevation view being an identical image thereof;

FIG. 3 is an enlarged front elevation view of the surgical saw blade teeth of FIG. 1; and,

FIG. 4 is a perspective view of the surgical saw blade teeth of FIG. 1.

The broken lines showing portions of the surgical saw blade teeth are included for the purpose of illustrating environmental structure and forms no part of the claimed design.
